UNITED STATES PATENT OFFICE.

GEORGE W. SCOTT, OF WASHINGTON, DISTRICT OF COLUMBIA.

DESIGN FOR A CANE-HANDLE.

SPECIFICATION forming part of Design No. 21,976, dated November 8, 1892.

Application filed October 15, 1892. Serial No. 448,014. Term of patent 3½ years.

To all whom it may concern:

Be it known that I, GEORGE W. SCOTT, a citizen of the United States, residing at Washington city, in the District of Columbia, have 5 invented and produced a new and original Design for Cane-Handles, of which the following is a specification.

The object of this design is to provide a novel, handsome, and ornamental cane-handle 10 which presents a characteristic and distinguishing appearance to the eye.

The design consists, essentially, in a cane-handle having the representation of the head of Christopher Columbus and of a sailing ship 15 and an inscription panel or space, the ship being designed to represent the *Santa Maria*.

The design is illustrated by the accompanying drawings, which are made on an enlarged scale to facilitate illustration.

20 Figure 1 is a top plain view of the cane-handle. Fig. 2 is a side elevation of the same, and Fig. 3 is a similar view looking at the opposite side of the cane-handle.

In the drawings the numeral 1 indicates a 25 cane having a handle which gradually increases in diameter from the point of attach-

ment to the cane to an annular ornamental bead 2 at the upper end. The top portion of the handle is composed of a convex disk or plate 3, which rises slightly above the ornamental bead 2 and bears a representation of the head of Christopher Columbus. The tapering handle is provided at one side with a representation of a sailing ship with the sails unfurled and is designed to represent the 35 *Santa Maria*. The side of the handle opposite the representation of the ship is provided with an inscription panel or space 4, which, as shown, is inclosed by a border 5.

The design provides a symmetrical and 40 beautiful cane-handle which presents a distinguishing appearance to the eye.

What I claim is—

The design for a cane-handle, substantially 45 as shown and described.

In testimony whereof I have hereunto set my hand in the presence of two subscribing witnesses.

GEO. W. SCOTT.
